UNITED STATES PATENT OFFICE.

CHARLEY MERRITT McFATRIDGE, OF MORAVIA, IOWA.

WIRE-BENDER.

SPECIFICATION forming part of Letters Patent No. 734,350, dated July 21, 1903.

Application filed November 4, 1902. Serial No. 130,034. (No model.)

To all whom it may concern:

Be it known that I, CHARLEY MERRITT McFATRIDGE, a citizen of the United States, residing at Moravia, in the county of Appanoose 5 and State of Iowa, have invented certain new and useful Improvements in Wire-Benders; and I do hereby declare the following to be a full, clear, and exact description of the invention, such as will enable others skilled in the 10 art to which it appertains to make and use the same, reference being had to the accompanying drawings, and to the figures of reference marked thereon, which form a part of this specification.

This invention relates particularly to a device for bending wires to a suitable shape to form ties to attach electric conducting-wires to insulators, the wires so formed being what are known as "tie-wires."

It has been found that tie-wires of considerable size are not easily bent by hand or pincers and when so bent are apt to be uneven and fit the insulator poorly. The object of my invention is to form a simple device which will remedy these defects and bend tie-wires to a desired exact form quickly and easily.

The device comprises a former secured to a base-board and a pair of levers which will 30 bend the wire around the former, and is illustrated in the accompanying drawings, in which—

Figure 1 is a plan view before the wire is bent. Fig. 2 is a similar view after the wire 35 is bent. Fig. 3 is a side elevation.

Referring specifically to the drawings, the base-board is indicated at 6. The former-block 7 is secured to this board, and the block has preferably a groove 7^a to hold the wire.

8 indicates a pair of levers, which are pivoted to the top of the block conveniently by the bolt 7^b, by which the block is secured to the base-board. The levers have studs 8^a

depending therefrom, and the studs are preferably headed, as at 8^b, to prevent the wire 45 slipping. They are adjustable on the levers to vary the distance from the pivot by means of slots 8^c, the ends of the studs being screw-threaded and provided with binding-nuts 8^d above and below the levers, whereby the studs 50 may be adjusted in the slots to the desired position.

To give the free ends of the tie a desirable outward flare, a block 9 is employed. This is secured to the base-board and is provided 55 with grooves 9^a to receive and shape the wire.

In operation a piece of wire the desired length is placed between the back of the former-block and the studs, as shown in Fig. 1. The levers are then brought around oppositely, bending the wire around the former, which, it may be understood, is the same size as the insulators on which the ties are to be used. The loop for the insulator is thus formed, and when the ends of the wire strike 60 the block 9 they are caused to flare to the desired extent by the pressure of the levers at the neck of the loop. The ties may thus be formed rapidly and true to the exact shape required to fit the insulators and avoiding the 65 laborious and unsatisfactory bending by hand or pincers.

What I claim is—

A wire-bender comprising a former-block, and a reverse-bending block spaced from the 75 former, and a pair of oppositely-working levers fulcrumed on the former-block and having depending studs bending the wire around the former and between the blocks, substantially as described.

In testimony whereof I affix my signature in presence of two witnesses.

CHARLEY MERRITT McFATRIDGE.
